(57) **CLAIM**

I claim the ornamental design for a memory card recorder for a surveillance video camera, as shown and described.

DESCRIPTION

FIG. 1 is a top perspective view of a memory card recorder for a surveillance video camera of the present invention;
FIG. 2 is a front view thereof;
FIG. 3 is a top view thereof;
FIG. 4 is a first side view thereof;
FIG. 5 is a second side view thereof;
FIG. 6 is a bottom view thereof; and,
FIG. 7 is a rear view thereof.
